(57) **CLAIM**

The ornamental design for a storage bed for vehicle, as shown and described.

DESCRIPTION

FIG. 1 is a perspective view of the design of the storage bed for vehicle, shown in a condition of use;

FIG. 2 is an enlarged perspective view of the storage bed for vehicle shown in FIG. 1;

FIG. 3 is a top view thereof;

FIG. 4 is a bottom view thereof;

FIG. 5 is a front view thereof;

FIG. 6 is a back view thereof;

FIG. 7 is a left view thereof; and,

FIG. 8 is a right view thereof.

The broken lines illustrate portions of the storage bed for vehicle which form no part of the claimed design. The broken lines depicting a vehicle bed in FIG. 1 show environmental structure which forms no part of the claimed design.

1 Claim, 6 Drawing Sheets
